UNITED STATES PATENT OFFICE.

CHARLES A. TATUM, OF NEW YORK, N. Y.

DESIGN FOR A HOT-WATER BOTTLE.

SPECIFICATION forming part of Design No. 30,475, dated April 4, 1899.

Application filed March 10, 1899. Serial No. 708,601. Term of patent 7 years.

To all whom it may concern:

Be it known that I, CHARLES A. TATUM, a citizen of the United States, residing at New York city, borough of Manhattan, county and State of New York, have invented and produced a new and original Design for Hot-Water Bottles, of which the following is a specification.

The leading feature of my design is a hot-water bottle substantially as embodied in the accompanying drawing—that is to say, a hot-water bottle having a surrounding trimming of a color contrasting with the tint or color of the body portion of the bottle,

In the drawing, *a* is the body of the bottle, and *b* a surrounding trimming contrasting in color or tint with the body. The drawing also embodies the rim-trimming *b*, the neck-trimming *c*, and the hanger-trimming *d*, all contrasting in tint or color with the body portion.

What I claim, and desire to secure by Letters Patent, is—

The design for a hot-water bottle substantially as shown and described herein.

CHARLES A. TATUM.
